UNITED STATES PATENT OFFICE.

CHARLES EDWARD GRELLE, OF PORTLAND, OREGON.

DESIGN FOR A LAMP-POST.

42,688.

Specification for Design.

Patented July 2, 1912.

Application filed March 23, 1912. Serial No. 685,851. Term of patent 7 years.

To all whom it may concern:

Be it known that I, CHARLES EDWARD GRELLE, a citizen of the United States, and a resident of the city of Portland, county of Multnomah, and State of Oregon, have invented a new, original, and ornamental Design for a Lamp-Post, of which the following is a specification, reference being had to the accompanying drawing, forming part thereof.

The figure of the drawing is a perspective view of a lamp-post, showing my new design.

I claim:

The ornamental design for a lamp-post, as shown.

CHARLES EDWARD GRELLE.

Witnesses:

CECIL LONG,
W. LEWIS COOK.
